J. Augsburger,

Cattle Pump,

N° 26,465.

Patented Dec. 20, 1859.

UNITED STATES PATENT OFFICE.

JOHN AUGSPURGER, OF TRENTON, OHIO.

CATTLE-PUMP.

Specification of Letters Patent No. 26,465, dated December 20, 1859.

To all whom it may concern:

Be it known that I, JOHN AUGSPURGER, of Trenton, Butler county, Ohio, have invented new and useful Improvements in Cattle-Pumps; and I do hereby declare the following to be a full, clear, and exact description of the same, reference being had to the accompanying drawings, making part of this specification.

10 My invention relates to pumps to which the weight of cattle is applied as a power in raising water for their own use from wells, &c., and consists in a device for preventing concussion and violence at the termination 15 of the upward motion of the bucket, and an arrangement by which the quantity of water raised from the well is at all times proportioned to the weight of the animal so that the speed of the bucket in being raised from 20 the well may be substantially the same under the operation of different weights of animals; and also in various minor improvements hereinafter described.

In the accompanying drawings, Figure 1 25 is a perspective view of an apparatus embodying my invention. Fig. 2 is a longitudinal section of the same. Fig. 3 is an enlarged plan of the automatic gates. Fig. 4 is an enlarged vertical section of the bucket 30 and Fig. 5 a plan of the same.

A is a fixed platform to which the movable platform B, is hinged at C.

D is a frame in which the pulley E, brake wheels F F and axle G are supported and 35 work on suitable friction rollers.

H is a platform hinged to platform B at a, and connected by bell cranks b b', rods and chains c c', to the axles of gates I, I.

The platform B is that on which the animal to be watered walks and lowers by his own weight, and through the following connections hoists the bucket from the well. The platform is connected by suitable straps or chains to the axle G, and the pulley E is similarly connected to the bucket K, the sizes of pulley E and axle C bearing the same relation to each other as do the respective distances required to be traveled by bucket and end of platform B.

50 M are guide rods on which the ears d of the bucket are made to slide in rising.

N N' are levers hinged to the frame D at e e' and connected together by the rods O. The levers N are provided on their under 55 sides with the brake springs f (which may be coiled springs or straight as shown).

The levers are balanced by weights P so that when the platform is at its highest position the springs f may rest easily on or a little above the brake-pulleys F. The 60 springs are brought forcibly to brake upon the pulleys F (when the momentum of descending platform B is required to be checked) by the said platform when near its lowest position being caused to act upon 65 the levers N', and produce the brake pressure.

The bucket K is provided with a clapper valve R which allows the bucket to fill quickly when lowered into the well. Its 70 discharge pipe g has a valve g' fitted on its inside which keeps the discharge closed till the bucket is raised so high that the trigger h, may be pressed down by passing stop s when the valve is opened and the water allowed to escape into the trough G'. The weight of the platform B when unoccupied is through wheel and axle overbalanced by the weight of the bucket, so that on the retirement of each animal from the platform 80 the bucket lowers quickly into the well to be refilled. The quantity of water raised at each elevation of the bucket is by the following device proportioned to the weight of the animal on the platform. A rod i is fitted to 85 slide vertically in the bucket and provided inside the bucket with a valve k, and outside with a float l. The hole in the bucket through which the valve rod passes is made considerably larger than the rod so that a 90 communication may exist between inside and outside of bucket through its bottom when the valve k is raised. The tendency of the float l is to keep the valve k raised when the bucket is lowered into the water and by 95 its weight to close it after leaving the water. The time occupied in the bucket leaving the water determines the quantity of water left in it after clearing the surface when the valve k closes. Thus heavy cattle by their 100 power to raise the bucket more quickly than lighter ones, give less time for the water in the bucket to escape at valve k, before it closes, and in consequence are compelled to draw up more water. By the regulation of 105 the quantity of water raised in proportion to the weight of the animal an easy uniform motion is given to the platform.

T is a check rope connected to platforms A and B to limit the elevation of the latter. 110 Each animal on entering the gates I I and stepping on platform H presses it down and

through its connections *b b'*, *c c'* closes the gates behind him and prevents entrance of others, and as in retiring after raising the bucket and drinking he has to pass the gates before another animal can enter, the platform *B* has time to resume its elevated position, and the bucket *K* to be refilled.

m m are loaded chains used to open the gates *I I* when the animal steps off the platform *H*. The trough *G'* is provided with a valve *n* weighted so that when the platform is lowered for the trough to receive water it may close and prevent water escaping till the animal is satisfied. It is kept open in the platforms elevated position by contact with the block *U* on its trigger *o* for the purpose of allowing all water that may be left in the trough to escape to prevent freezing up in winter.

20 *p* is a spout forming communication from the bucket to the trough *G'*.

I am aware that it is common to operate a valve by means of a float; but know of no instance in which the parts have been ar-

ranged in the manner which I have exhibited so as to hold the valve open for a period after the bottom of the bucket is raised above the water, and thus prevent more water remaining in the bucket than can be effectually raised by the weight of the animal.

25

30 I claim as new and of my invention herein and desire to secure by Letters Patent,

1. The combination and arrangement of the platform *B*, levers *N*, *N'*, springs *f*, weights *P*, rods *O*, and break wheels *F*, 35 operating substantially as and for the purpose set forth.

2. The arrangement of the float *l* rod *i* and valve *k* in the described combination with and relation to the bucket *K* and hinged platform *B*, operating in the manner and for the purpose explained.

40

In testimony of which invention, I hereunto set my hand.

JOHN AUGSPURGER.
